(57) **CLAIM**

The ornamental design for a transom saver for an outboard motor, as shown and described.

DESCRIPTION

FIG. 1 is a perspective view of a transom saver for an outboard motor according to our new and ornamental design;

FIG. 2 is a front view thereof;

FIG. 3 is a rear view thereof;

FIG. 4 is an end view thereof;

FIG. 5 is an opposite end view thereof;

FIG. 6 is a top view thereof; and,

FIG. 7 is a bottom view thereof.

The broken lines illustrate the aspects of the transom saver for an outboard motor that are not part of the claimed design.
